CENTERLESS GRINDING MACHINE

Albert G. Belden and Raymond A. Cole, Worcester, Mass., assignors to Norton Company, Worcester, Mass., a corporation of Massachusetts

Application January 23, 1935, Serial No. 3,022

22 Claims. (Cl. 51—103)

The invention relates to grinding machines particularly of the so-called centerless type.

One object of the invention is to provide a centerless grinder which, so far as stopping the action when the work-piece arrives at finished size is concerned, is self-acting or automatic. Another object of the invention is to provide a centerless grinder of great precision, adapted to produce finished work-pieces varying from each other in diameter by a tolerance amount of very small dimensions. Another object of the invention is to provide an apparatus in which the advantages of ready loading and high production of the centerless grinding principle and the advantages of close tolerance automatically attained are both or all of them achieved. Other objects will be in part obvious or in part pointed out herein-after.

The invention accordingly consists in the features of construction, combinations of elements, and arrangements of parts as will be exemplified in the structure to be hereinafter described, and the scope of the application of which will be indicated in the following claims.

In the accompanying drawings, in which is shown one of various possible embodiments of the mechanical features of this invention,

Figure 1 is a front elevation of a grinding machine embodying the invention, the left-hand part of the front frame member being broken away to show certain feed slide actuating mechanism;

Figure 2 is an enlarged view showing the grinding and regulating wheels and the sizing or gauging mechanism in cross-section;

Figure 3 is a horizontal sectional view taken on the line 3—3 of Figure 2;

Figure 4 is a wiring diagram.

Referring first to Figure 1, we provide a machine base 10 which may have any suitable or desired shape and preferably is fairly massive in order to provide a rigid support for the mechanism to be described. Suitably mounted on the machine base 10 is a regulating wheel 11, and mounted on a feed slide 12 is a grinding wheel 13. Both the regulating wheel 11 and the grinding wheel 13 may be abrasive wheels in which abrasive grain such as of alumina (Al_2O_3) or silicon carbide (SiC) is bonded with a suitable bond, as a vitrified bond, or a resinous bond, including shellac and phenolic condensation products, or rubber. The particular wheels will be chosen with due regard to the material of the work-piece and the type of finish to be imparted thereto, and the regulating wheel 11 preferably

has a denser structure than the grinding wheel 13, and so far as the features of this invention are concerned the regulating wheel 11 may be other than an abrasive wheel, and any substance or rotary tool which will cut may be used for the wheel 13.

Preferably the abrasive wheel 13 is driven at a high peripheral velocity in the direction of the arrow thereon, Figure 1, and preferably the regulating wheel 11 is driven at a relatively low peripheral velocity, in the direction of the arrow thereon, Figure 1.

Referring now to Figures 1 and 2, the wheel 11 is formed in two sections 11a and 11b which, from the manufacturing standpoint, may be separate wheels or articles in the first instance. We desire to provide a space between elements of the regulating wheel 11 in which certain parts of our gauging instrumentality, hereinafter described, may be located, and we may provide this space by forming a groove in an integral wheel 11, or as illustrated in Figure 3 we may provide separate independent wheel sections 11a and 11b united together as illustrated in Figure 3 and as now to be described for the preferred embodiment of the invention. As illustrated in Figure 3, the wheel or wheel section 11a has a lead center 14a while the wheel or wheel section 11b has a lead center 14b. We provide a sleeve 15 having a tapered bore, a flange 16 at one end, and screw threads 17 at the other end. The outside of the sleeve 15 is cylindrical, and upon it we place the wheels 11a and 11b, the lead centers 14a and 14b just fitting the sleeve 15. Between the lead centers 14a and 14b we place a spacer ring 18. A washer 19 and a pair of nuts 20—20 whose threads fit the threads 17 of the sleeve 15 complete the assembly, the lead center 14b being held against the flange 16, and the lead center 14a being held in position by the washer 19 and nuts 20, which may be tightened, with the spacer 18 interposed between the lead centers 14a and 14b. Thus is formed a unit comprising two wheel sections 11a and 11b which, in this embodiment of the invention, are of the same diameter. While the wheel sections 11a and 11b need not be of the same thickness, we have shown them so, and in that way they are interchangeable.

The entire unit just described, including the sleeve 15 and the wheel sections 11a and 11b, we mount upon the tapered end 21 of a wheel spindle 22, the tapered bore of the sleeve 15 fitting the taper of the end 21. The spindle 22 has a threaded end 23 adapted to receive a couple of nuts 24—24 and by tightening these we affix

wheel unit 11 upon the tapered portion 21 of the spindle 22.

Referring now to Figures 1, 2 and 3, uprising from the machine base 10 we provide a wheel 5 mounting 25 and in this wheel mounting 25 we locate a journal 26 which journals the spindle 22. As indicated in dotted lines on Figure 1, the wheel spindle 22 has a pulley 27 on its rear end and this is connected by means of a belt 28 with 10 a pulley 29 in or on the machine base. The pulley 29 may be driven from any source of power desired and is driven at a rate to impart the speed heretofore defined to the wheel 11.

Referring again to Figure 2, the wheel 13 which 15 is the grinding or cutting wheel may be an integral piece, and desirably it has a lead center 30. We provide a sleeve 31 having a tapered bore, with a flange 32 at one end and a screw threaded portion 33 at the other end. By means 20 of a washer 34 and a pair of nuts 35 the wheel 13 is mounted upon the sleeve 31, and the unit may be mounted upon a spindle 36 having a tapered portion 37 by means of a pair of nuts 38 and a threaded portion 39 of the spindle 36, the 25 construction in this respect being similar to that already described in connection with the wheel 11.

Referring particularly to Figure 1, we provide a wheel mounting 40 extending upwardly from the slide 12 and, referring to Figure 3, this 30 wheel mounting supports a journal 41 which journals the spindle 36. Referring again to Figure 1, at the rear of the spindle 36 we provide a pulley 42 which may be driven by a belt 43 from a pulley 44 on a shaft 45. Pulley 44 and 35 shaft 45 are, the same as pulley 29, to be considered as prime movers, and may themselves be driven from any suitable source of power, the rate and direction of rotation being determined in accordance with considerations previously 40 stated, that is so as to drive the grinding or cutting wheel 13 at a relatively high speed so far as its peripheral velocity is concerned. From the shaft 45 we actuate the in and out feeding of the wheel 13 by movement of the feeding slide 45 12 as will now be described. We note that the arrangement shown in Figure 1 may be used despite the motion of the slide 12, for the actual distance that this slide travels may be very short in comparison with the distance between pulleys 50 42 and 44, and also the translation of the slide is in a line perpendicular to the plane connecting the axes of these pulleys, and belts, particularly leather belts, are known to have considerable elasticity.

55 Referring now to Figure 1, fastened to the shaft 45 is a beveled gear 50 which meshes with a beveled gear 51 which in turn is fastened to a shaft 52 that projects from a gear box shown in section in Figure 1 the side frame members of 60 which are designated by the numerals 53 and 54. The shaft 52 is journaled in each of these side frame members which likewise journal shafts 55, 56 and 57, all of these shafts being, in this embodiment of the invention, parallel to each 65 other and collectively mounting reduction gearing and reversing mechanism. Still considering Figure 1, and remembering that shaft 52 is constantly driven by means of the beveled gearing described, and noting that the direction of rotation is indicated by the arrow in Figure 1, a spur gear 58 is fastened to the shaft 52 which meshes with and drives a spur gear 59 that is revolvable on the shaft 55. The spur gear 59 meshes with a spur gear 60 revolvable on the shaft 56; a spur 70 gear 61 is attached to the spur gear 60 and the

former meshes with a spur gear 62 that is attached to a spur gear 63, the unit 62, 63 being mounted on the shaft 51. The gear 63 meshes with a gear 64 which is mounted on a stud 65 projecting from a separate bracket 66. The gear 64 meshes with a gear 67 which is connected to a gear 68, the unit gears 67 and 68 being revolvably mounted on the shaft 56. Suitable spacing collars are provided as illustrated, and the train of gear described greatly decreases the angular velocity of a final gear 69 which, the same as gear 59, is revolvably mounted on the shaft 55. The direction of rotation of the gears is indicated by arrows in Figure 1. Thus the gear 59 rotates in one direction, while the gear 69 rotates in the other direction at but a fraction of the angular velocity of the gear 59. By securing the shaft 55 to one or the other of the gears 59 or 69, or by unclutching it from both of them, the shaft 55 may be driven in one direction with a high 20 angular velocity, or in the other direction with a low angular velocity, or stopped altogether, and the clutching mechanism will now be described.

Mounted on the shaft 55 and connected to it by a sliding keyway or the like so that it shall 25 revolve in unison with the shaft 55 but be translatable thereon, is a double faced clutch member 70 having a groove 71 into which projects a pair of pins 72 (only one shown) on the forked end of a lever 73 which is pivotally mounted on a shaft or stud 74 projecting from the machine base 10. The gear 59 has clutch teeth 75 facing to the right, while the gear 69 has clutch teeth 76 facing to the left, which are shown in engagement with the right-hand clutch teeth of the clutch member 70. In this position of the parts, power is transmitted through the reduction gearing described to drive the shaft 55 slowly in what we may call the feed direction. When, by shifting the lever 73, the left-hand clutch 30 teeth of the clutch member 70 are caused to engage with the right-hand clutch teeth 75 of the gear 59, the shaft 55 is driven rapidly in the opposite or, as we may call it, withdrawal direction. 35

Still referring to Figure 1, mounted on the end of the shaft 55 is a beveled gear 80 which meshes with a beveled gear 81 on the lower end of a vertical shaft 82 that is supported by journals 83 and 84 attached to the machine base 10. On the upper end of the shaft 82 is a beveled gear 85 meshing with a beveled gear 86 loosely mounted on a screw shaft 87. Beveled gear 86 has a long hub 88 on the right-hand end of which are clutch teeth 89 adapted to mesh with clutch teeth 90 on a member 91. The member 91 is keyed to the shaft 87 but is translatable thereon, and can be controlled by means of a plunger rod 92 with handle 93 projecting from a hand wheel 94 located on the left-hand side of the machine as shown in Figure 1. The hub 88 is journaled in a journal 95 which, together with journal 96 in the machine base 10, serves to support the screw shaft 87. 40

By means of the knob 93 on the end of the plunger rod 92 the screw shaft 87 can be clutched to the gear 86 or disconnected therefrom. In the former event the prime mover acting through the transmission described actuates the screw shaft 87; in the latter event it may be actuated by the hand wheel 94. The screw shaft 87 has feed slide translating screw threads cut therein at the right-hand portion thereof, as indicated in Figure 1, and this portion of the screw shaft 87 passes through a nut 98 fastened to the underside of the slide 12 so that rotation of the shaft 87 translates 45

the slide 12. The slide 12 preferably is carried on V and flat ways, not shown, such being well known in practically all the machine tool industries and having been used previously in grinding machines. The screw shaft 87 is held from translation by a thrust bearing, which might be the bearing 96 or may be a separate bearing, not shown.

Still referring to Figure 1, projecting from the front of the base 10 is a hood 100 of substantial strength and rigidity, which may be of the shape shown, and which provides a horizontal surface upon which to mount the steady rest, and which provides another horizontal surface upon which to mount the gauging apparatus. The hood 100 also may serve to collect coolant which is discharged upon the work-piece as the grinding takes place, and it may act as a wheel guard to protect the operator from injury should either of the wheels explode, or comply with rules and regulations of competent governmental authorities for the guarding of rapidly rotating wheels. Extending upwardly from the inside lower plane surface of the guard 100 is a standard 101 to which, as better shown in Figure 2, is fastened a steady rest 102 by means of bolt 103. The upper part of the steady rest 102 is forked as indicated by showing it in elevation in Figure 2, the lower part being cross-sectioned to show that it is solid. The steady rest 102 has a pair of work-piece supporting surfaces 104 which are inclined upwardly to the left as viewed in Figure 2, whereby the work-piece is supported by a surface tangent to it on a line somewhere in the neighborhood of 45 degrees removed from the line of tangency between the work-piece and the grinding wheel 13.

The work sizing or gauging device may be similar to that disclosed in our United States Patent No. 1,911,552 granted May 30, 1933, and in this specific embodiment of our present invention we illustrate and describe elements of our patented gauging device, and the description herein may be supplemented by reference to the above-numbered patent. The gauging elements of our sizing device fit in the space between regulating wheel sections 11a and 11b and in the space between the forks of the upper forked portion of the steady rest 102, desirably the latter space being equal in width to the former space.

Referring now to Figure 2, we provide an L-shaped casing 105 having a caliper head 106 which has a pair of adjustable contact screws 107 and 108 and a vertically movable plunger 109 as described in the aforesaid patent. We also provide bell crank lever 110 mounted on a stud 111 together with adjustable contact elements 112 and 113 and associated parts including the spring 114 which urges the bell crank lever 110 counter clockwise and the plunger 109 downwardly.

The gauging action per se takes place as described in the patent and the bell crank lever 110 is connected to a battery or other source of low voltage electric energy as disclosed in the wiring diagram of Figure 4, while contact element 112 is connected to a relay 115 and the contact element 113 is connected to relay 116. We prefer to use the relays and solenoids as disclosed in our patent, and in the operation of the caliper device an electric circuit is first completed through the contact element 112, and thereafter through the contact element 113, energizing first the relay 115 and thereafter the relay 116. Referring now to Figure 4, the relay 115, when

energized, causes high voltage or high power current to energize a solenoid 117, while the relay 116 causes energization of a solenoid 118. The circuits will be perfectly clear from inspection of Figure 1, and furthermore are described in the aforesaid patent, and therefore we have refrained from giving every wire a reference character. As in the disclosure of the aforesaid patent, we prefer to use the solenoid 117, indirectly energized by contact 112, to stop the in-feed of the grinding wheel 13, using the solenoid 118, indirectly energized by the contact 113, to cause the feed slide 12 to run the grinding wheel 13 outwardly. As disclosed in the aforesaid patent, in a grinding machine which is taking a fairly heavy cut, stopping of the in-feed does not terminate the grinding, because the machine parts are under some tension and act as a spring with respect to the very close tolerances involved in precision grinding, and hence grinding proceeds even after the feed is stopped, and this phenomenon is known as "sparking out". For centerless grinding of work-pieces to exact size we propose to reduce the work-pieces in diameter to a dimension somewhat above the desired finished size and at that time to stop the in-feed; the remainder of the grinding is a finishing or sparking out operation and when the work-piece comes to the exact desired size (exact within very close limits) the feed slide 12 runs out pursuant to closing of the contact between bell crank 110 and contact element 113, and grinding and finishing thereby definitely cease. As in the aforesaid patent, low voltage energy is used for the circuits involving the actual contact elements, thus avoiding pitting and arcing as much as possible, while high power circuits are used to energize the solenoids 117, 118 thus obtaining a strong and positive action, and this is made possible by the use of the relays 115, 116.

We support the gauging or caliper mechanism from the upper part of the hood 100. As shown in Figure 2, a clamping device 120 adjustably holds the casing 105 from falling below a certain limit supposing there is no work-piece in the head 106. The casing 105 extends through an opening 121 in the hood 100 which is over-size, and a spring 122 extending between the clamp 120 and a post 123 urges the casing 105 clockwise, thus to maintain the screw 107 in contact with the work-piece and furthermore in order to carry the work-piece away from the regulating wheel 11 when the carriage 12 runs out. A stop arm 124, above the spring 122, acts with the spring to exert a couple upon the casing 105. There is a limit to possible angular motion of the casing 105, determined by the size of the opening 121, and the amplitude may be varied by means of adjustment screws or the like, not shown.

Referring now to Figure 1, the lever 13 which controls the motion of the carriage 12 has, as previously stated, three positions, the middle position being the neutral position, the left-hand position being the feed position wherein the slide 12 moves to the right, and the right-hand position being the rapid withdrawal position, wherein the slide 12 moves outward rapidly. We provide a three-position cam 125 acted upon by a spring detent 126, so that the lever 13 may be held in any one of its three positions, and urged into any one of them when the various high points of the cam 125 have been passed by the dagger portion of the detent 126, and for convenience this cam

125 has been marked RNF which letters respectively mean reverse, neutral and feed. In order to stop the reverse or outward movement of the slide 12, attached to it is a downwardly extending rigid arm 130 carrying an adjustable contact rod 131 which is in line with the upper part of the lever 73.

Referring now to Figures 1 and 4, the solenoids 117 and 118 operate the lever 73 in the following manner: The upper part of lever 73 has a laterally extending pin 132 engaging a spool 133 on a solenoid rod 134 which is made of magnetic and non-magnetic material attached together in such manner that energization of either solenoid 117, 118 urges the solenoid core rod 134 to the right. Assuming the lever 73 is in its left-hand position as shown in Figure 1, and remembering that the solenoid 117 is first energized, this action as stated draws the rod 134 to the right. On the right-hand end of rod 134 is an upwardly extending projection 135 in position to strike an inclined member 136 attached to a switch arm 137 which, as shown in Figure 4, is in circuit between the solenoid 117, the relay 115, and the high voltage power lines. Thus as the rod 134 is drawn to the right, and as the detent 126 drops into neutral position, the circuit through solenoid 117 is broken and feed of the slide 12 is stopped.

Assuming now the lever 73 is in central or neutral position, grinding nevertheless continues as described, until the final contact is made through the contact element 113, energizing the relay 116, which in turn energizes the solenoid 118, and again urges the core member 134 to the right 35 thus moving the lever 73 to its right-hand or reverse position and causing the slide 12 to run outwardly. As the dagger part of the detent 126 drops into the reverse notch of the cam 125, an upwardly extending projection 140 carried by the left-hand end of the solenoid rod 134 strikes an inclined member 141 on a switch arm 142 which is in circuit between solenoid 118, relay 116 and the power line, shown in Figure 4, and thus this 40 circuit is opened. The slide 12 continues outwardly until the rod 131 strikes the lever 73, which action forces this lever into neutral position. Preferably the switch arm 137 is loosely pivoted so that, when starting up the machine again, the moment the lever 73 is returned to feed 45 position the circuit at this switch will be closed, but preferably the switch arm 142 is mounted on a friction pivot so that it will remain open despite the fact that member 140 has left the inclined member 141, in order to save useless 50 energization of the solenoid 118. In order to close this switch 142 again when a new grinding operation is commenced, we provide a projection 145 on the lever 73 adapted to engage an upwardly extending arm 146 of the switch member 142 when the lever 73 is pulled to the left. The lever 73 is preferably keyed to its pivot shaft 74, so that by means of a lever 150 on the front or back of the machine the transmission may be 55 controlled.

Assuming that the operator finds the machine with the grinding wheel 13 withdrawn from the work-piece and the lever 73 in mid or neutral position, after adjusting the caliper device for a particular size of work-piece, the operator 60 raises the plunger 109, as by means of a pin 151, Figure 2, and inserts a work-piece between the screws 107, 108 and the plunger 109. The weight of the casing 105 positions the work-piece against the surfaces 104 of the steady rest 102, and, assuming the regulating wheel 11 is rotating, the 65

work-piece is rotated. The spring 122 is urging the gauging head 106 to the left, in order to secure the three-point contact, and the spring 114 is strong enough to overcome the weight of the casing 105, and actually urges the screw 108 upwardly. When the contact is made at contact element 112 as described, the lever 73 is shifted to neutral position as already set forth and the finish grinding proceeds until the desired size is reached, whereupon the slide 12 runs out and stops. The spring 122 carries the work-piece away from the regulating wheel or at least removes the pressure between these elements as soon as the wheel 13 runs out, but at all events the work-piece cannot follow wheel 13 on account of the limits of the opening 121. With the wheel 13 out of the way the operator can replace the finished work-piece with an unfinished one and, by merely shifting the control lever 150, cause the machine to resume grinding. The shape of the steady rest 102 has been chosen to insure grinding of work-pieces to a true cylindrical form, properly supporting the thrust of the grinding wheel, and the thrust of the screw 107 is opposed to the thrust of the grinding wheel. 25

It will thus be seen that there has been provided by this invention an apparatus in which the various objects hereinabove set forth, together with many practical advantages, are successfully achieved. As many possible embodiments may be made of the above invention, and as many changes might be made in the embodiment above set forth, it is to be understood that all matter as hereinbefore set forth and as shown in the accompanying drawings is to be interpreted as illustrative and not in a limiting sense. 30

We claim:—

1. In an external centerless grinding machine, a grinding wheel having a diameter greater than that of the largest work piece adapted to be 40 ground by the machine, a regulating wheel, a steady rest, a caliper device formed to contact the exterior surface of a work piece, and means operated thereby to cause a grinding operation to determine and cease when the work piece comes to the desired finished size.

2. In an external centerless grinding machine, a grinding wheel having a diameter greater than that of the largest work piece adapted to be 50 ground by the machine, a regulating wheel, a work rest, a caliper device formed to contact the exterior surface of a work piece, a feeding mechanism to move relatively the grinding wheel and regulating wheel, and means controlled by the caliper device to arrest the movement of 55 said feeding mechanism.

3. In a grinding machine, a work throat comprising a grinding wheel, a regulating wheel and a work rest, and precision means comprising a caliper device contacting the work at opposite ends of a diameter to regulate the amount of material removed from the work-piece. 60

4. In an external centerless grinding machine, a grinding wheel having a diameter greater than that of the largest work piece adapted to be 65 ground by the machine, a regulating wheel, a wheel slide for one of said wheels, translation means to move said slide, a support for the work piece, and work piece exterior contacting caliper means to arrest the movement of the slide 70 when the work piece arrives at a certain size.

5. In an external centerless grinding machine, a grinding wheel having a diameter greater than that of the largest work piece adapted to be 75 ground by the machine, a regulating wheel, a

wheel slide for one of said wheels, translation means to move said slide, a support for the work piece, a caliper device formed to contact the exterior surface of a work piece, and means actuated by said caliper device to cause the translation means to separate said wheels when the work piece reaches a certain size.

6. In a grinding machine, a grinding wheel, a regulating wheel, a steady rest, a wheel slide, 10 translation means including a feed train to move said slide, a quick traverse train to withdraw said slide, clutching and reversing mechanisms to select one or the other of said trains and having a neutral position, and precision means automatically actuating said last-named mechanisms.

7. In a grinding machine, a grinding wheel, a regulating wheel, a slide arranged to move said grinding wheel with respect to a work-piece, a precision device to measure the size of the work-piece, 20 a transmission mechanism including a feed train and a quick movement train to move said slide, clutching and reversing mechanism for said transmission, and means controlled by said precision means to actuate said clutching and reversing mechanism.

8. In a grinding machine, a grinding wheel, a regulating wheel, a work contacting caliper, a lever controlled by said caliper, a contact element adapted to close a circuit when said lever 30 moves, a relay energized when said circuit is closed, a solenoid controlled by said relay, a clutch element actuated by said solenoid, a quick withdrawal transmission train controlled by said clutch element, and a slide carrying one of said 35 wheels and moved by said transmission.

9. In a grinding machine, a work contacting caliper device, a grinding wheel, and a two-part regulating wheel between the elements of which said work contacting caliper device is 40 located.

10. In a grinding machine, a pair of wheels on parallel axes, there being a groove in one wheel and a caliper device located in said groove.

45 11. In a grinding machine, three wheels, two of them mounted coaxially and the third on an axis parallel to the axis of the first two, and a caliper instrumentation mounted between the wheels, which are coaxial.

50 12. In a grinding machine, a grinding wheel having a grinding face, a work rest substantially as long as said face except for a cut-out intermediate the ends of the grinding face, and a caliper device located in said cut-out.

55 13. In a grinding machine, a grinding wheel having a grinding face, a regulating wheel having a face substantially conterminous with the grinding face except for a cut-out intermediate its ends, and a work caliper device located in 60 said cut-out.

65 14. In a grinding machine, a pair of wheels having opposed peripheries substantially conterminous except for a cut-out in one of them, and a work caliper device located in said cut-out.

70 15. In a grinding machine, a pair of wheels having opposed peripheries substantially conterminous except for a cut-out in one of them, a work rest having a cut-out substantially conterminous with the first mentioned cut-out, and a caliper device located in said cut-outs.

16. In an external centerless grinding machine, a grinding wheel having a diameter greater than

that of the largest work piece adapted to be ground by the machine, a regulating wheel, feeding means to feed one of said wheels towards the other one, a caliper device formed to contact the exterior surface of a work piece and therefore not affected by wear on said wheels, and means operated thereby to cause the grinding operation to cease.

17. In an external centerless grinding machine, 10 a grinding wheel having a diameter greater than that of the largest work piece adapted to be ground by the machine, a regulating wheel, a work rest, said wheels and rest being so aligned that the work piece is rotated in a fixed position and ground, and work exterior contacting caliper means to cause the grinding to proceed until the work reaches a predetermined size and then to cause the grinding to cease.

18. In a centerless grinding machine, a grinding wheel, a regulating wheel, a work rest, means 20 to cause said wheels to approach each other, reversing means for said last named means which when actuated causes the wheels to recede from each other, and work contacting caliper means to actuate said reversing means when the work-piece has reached a predetermined size.

19. In an external centerless grinding machine, 30 a grinding wheel having a diameter greater than that of the largest work piece adapted to be ground by the machine, a regulating wheel, means to hold a work piece in fixed position between said wheels, means to cause said wheels to approach each other, and means to arrest the approaching movement when the work piece reaches a predetermined size.

20. In an external centerless grinding machine, 35 a grinding wheel having a diameter greater than that of the largest work piece adapted to be ground by the machine, a regulating wheel, means to hold a work piece in fixed position between said wheels, means to cause said wheels to approach each other, and caliper means contacting the exterior of the work to cause said wheels to part when the work piece reaches a predetermined size.

21. In an external centerless grinding machine, 45 a grinding wheel having a diameter greater than that of the largest work piece adapted to be ground on the machine, a regulating wheel, means to hold a work piece in fixed position between said wheels, means to cause said wheels to approach each other, and caliper means located in the area defined by said grinding wheel and regulating wheel for arresting the means to cause said wheels to approach each other.

50 22. In an external centerless grinding machine, 55 a grinding wheel having a diameter greater than the largest work piece adapted to be ground by the machine, a regulating wheel having a diameter greater than the largest work piece adapted to be ground by the machine, a steady rest between said wheels and forming with them a grinding throat, a mounting for one of said wheels permitting it to be moved towards the other one to effect a plunge-cut grinding operation, and work size determining means to control the exterior diameter of the work piece irrespective of wear or reduction in diameter of either one of the wheels, said work size determining means acting during the actual grinding operation.
